UNITED STATES PATENT OFFICE.

WILLIAM B. EWING, OF CHICAGO, ILLINOIS.

STEAM GENERATOR.

Application filed November 12, 1921. Serial No. 514,607.

This invention relates in general to steam generators and has more particular reference to steam generators of the flash or coil type.

5 The principal object of my present invention is the provision of a steam generator for use in automobiles, motor trucks, and the like, which will have high efficiency under all conditions of use, which will be 10 wholly automatic in action and of small and compact construction.

My invention contemplates in this regard, improvement over prior similar constructions in the more efficient utilization of the 15 heat applied to the boiler.

Another important object of the invention is the provision of a generator consisting of relatively few parts, which may be cheaply manufactured, readily assembled, and unlikely to require frequent repair, replacement, or readjustment.

Another important object of the invention is the provision of a generator of the character described, the construction of which may 25 be readily understood by the average garage mechanic, the parts being so arranged that they may be easily removed and replaced, or readjusted as occasion may require.

Another highly important object of the 30 invention is the provision of a burner and combustion chamber in such a generator which are completely enclosed.

Another important object of the invention is the provision of a generator which will 35 permit the use of a condenser, forming with the generator, piping and engine parts, a closed system, so that the water employed may be used over and over again, the apparatus being so designed as to require a 40 minimum amount of addition of fresh feed water.

Another important object of the invention is the provision of a generator of the character described which will be so constructed 45 and arranged as to provide high velocity of moving water and steam through the tubes whereby to enable the generator to practically free the tubes of scale and other foreign matter so as to prevent appreciable deposit thereof.

Numerous other objects and advantages of the invention will be apparent from the following description which taken in connection with the accompanying drawing illustrates a preferred embodiment thereof.

Referring to the drawings:

Figure 1 is a transverse sectional view taken on the line I—I of Figure 2 of a generator embodying my invention, certain attendant parts being shown schematically. 60

Figs. 2 and 3 are sections taken respectively on the lines 2—2 and 3—3 of Fig. 1.

For the purpose of illustrating my invention, I have shown on the drawing a steam generator in which all of its several features 65 are embodied. It will, however, be readily manifest that some of the features may be omitted and all may be differently constructed and arranged without departing from the spirit or scope of this invention. 70

The embodiment of the invention shown on the drawing includes an outer casing 11, preferably comprised of a sheet metal outer shell 12 and an inner thick layer of heat insulating material 13, as asbestos fibre and the like. The outer shell is preferably made

in two parts together entirely enclosing the steam generating parts. A hollow tank 14 is provided within the casing, this tank in the present instance being of cylindrical 80 form and constituted of an outer wall 15, and inner wall 16, and top and bottom walls 17 and 18. This tank is so arranged within the casing as to form an outer space 21 between the outer face of the tank and the inner face 85 of the casing, which space constitutes an up-draft flue as will presently be more fully explained.

An annulus 22 closes the top of this space and an outlet 23 is provided at one side for the products of combustion. 90 The annulus 22 is fixed at its upper end to the casing and is fastened by bolts 19, to the tank, this arrangement supporting the tank in position. Insulating material 24 is provided upon the outer face of the tank. A

burner 25 is arranged just beneath the top wall 26 of the casing, having a gas inlet 27 and an air inlet 28. The burner openings 29 are arranged to direct the combustible mixture downwardly so that combustion occurs beneath the burner, the burner and tank being so arranged that this combustion occurs within the upper hollow end of the tank. Water is introduced into the tank from a feed pipe 31 which enters through 95 the casing at 32 between its separable halves. The pipe 31 within the casing is formed into a series of coils 33 about the tank and in the flue space 21, these coils 33 spiraling down to near the bottom of the tank at 34 from 100

105

the casing at 32 between its separable halves. The pipe 31 within the casing is formed into a series of coils 33 about the tank and in the flue space 21, these coils 33 spiraling down to near the bottom of the tank at 34 from 110

whence the coil is bent out into the insulation 13 at 35 to the bottom of the tank, then inwardly at 36 to beneath the tank and thence upwardly at 37 into a coupling 38 5 communicating within the tank itself.

The steam generator in the present instance is of the flash type and coils that will now be described are arranged in the path of the heated gases for the formation of the 10 steam. This path of heated gases is downwardly through the tank and thence upwardly about its outside. These coils have lower connection at 39 with a coupling entering into the bottom of the tank. They 15 are arranged serially as follows: The tube end 41 continues into an upwardly spiraling concentric coiling 42 and then in a downwardly spiraling 43, the coils 42 and 43 being located at the bottom part of the flue 20 space 21 and beneath the insulation 24. From the coils 43, the tube is brought inwardly as indicated at dotted lines 44 to an upwardly arranged series of coils, the individual members of each series being concentric and disposed horizontally. Each such 25 series is designated by reference character 45 from which it will be noted that the tube is coiled spirally a number of times at each horizontal level and from each such coiling 30 passes into a similar series immediately above until a point 46 is reached well up within the hollow of the tank. The centers of alternate series are somewhat offset as may be seen in Fig. 1. From the point 46, 35 the steam generating tube spirals upwardly into coils 47 to the upper tube end 48, which communicates with the top of the tank through a coupling 49. This coupling as shown in Figure 2 is arranged to introduce 40 the steam and such water as it may carry in a direction angular with respect to the side wall of the tank. The entrained water is therefore projected forcibly against the outer side wall by the swirling motion of the 45 steam. This produces a separation of the water from the steam and dryer steam results.

The steam is withdrawn from the tank for use by a tube 51. This tube communicates 50 with a coupling 52 at the top of the tank. From this coupling, the tube 51 is coiled downwardly at 52 within the coil 47 to just above the series of coils 45. From the coils 52, it is looped downwardly at 53 to near the 55 bottom of the tank and back up to 54 near the bottom of the coil 52. A second downward loop 54' is provided at right angles to the loop 53, this loop extending on up and out as indicated.

60 It will be noted that the generator in the present instance includes preheating coils 33, flash or steam generating coils 42, 43, 45 and 47, and superheating coils 52, 53 and 54. The products of combustion are of course 65 cooler from the zone of combustion pro-

gressively to the outlet 23 and it will be noted that the arrangement shown on the drawing results in subjecting the feed water pipes or coils 33 to the coolest portions or zones of the moving hot gases; that the coils 70 42 and 43 are located in the next warmer zone; those 45 in the zone still warmer; and those 47 in the actual zone of combustion; and that the superheating coils 52 are at the hottest zone of the apparatus. 75

If desired a steam gage 61 may be provided and communicate with an upper pipe 62 and a lower pipe 63 with the top and bottom of the tank. A pipe 64 is provided to be connected with a safety valve (not 80 shown) if desired, and an opening 65 through the casing to permit the provision of a pilot light (not shown) or the insertion of a match to light the burner.

The generator is well adapted to form 85 part of a closed steam and water circuit, the steam being condensed again and again after the steam has expended its power. A pipe or tube 67 leading from the engine 90 conducts the steam to a condenser shown diagrammatically in Fig. 1 at 66. From here the resulting water is carried to a combined float and valve chamber 68, from which a single pump 76 is adapted to return it 95 through the tube 31 to the tank. 95

The inside of the flash tubes is of small diameter, so that the water in moving through them travels at high velocity. It is discovered that water moving at high velocity through a tube will change from a 100 straight path of travel to an eddying or spiraling one, and that water thus traveling may be more quickly and easily heated. The velocity of the water results from gravity through difference of gravity levels by steam 105 generation, the bubbling or ebullition, and the steam velocity itself.

It is thought that the invention and many of its attendant advantages, will be understood from the foregoing without further 110 description and it will be manifest that various changes may be made in the form, construction, and arrangement of the parts without departing from the spirit and scope of the invention, or sacrificing all of its 115 material advantages, the form hereinbefore described being merely a preferred embodiment thereof.

I claim:

1. A steam generator, comprising a casing, a tank providing an inner flue, and an outer flue in connection with said casing, water coils in the outer flue, flash coils in the inner flue, the arrangement of said coils being such that the flow of water through 120 the feed coils is in a reverse direction to the flow of steam in the flash coils. 125

2. A steam generator comprising a casing closed at its bottom, an annular tank within said casing and spaced from the bottom and 130

side walls thereof to provide a flue space, coils connected to said tank and arranged between said casing and tank within the inner wall of said tank, and a burner located 5 above the tank in position to direct heated gases down through the space within the inner wall of the tank, said gases then passing through said flue space between the tank and casing.

3. A steam generator, comprising a casing, a tank within said casing, a series of preheater coils, a series of flash coils, and a series of superheater coils, all connected to said tank, said connections being made at the top and bottom of said tank to permit 10 of the ready removal of said coils.

WILLIAM B. EWING.
